ATTORNEY

UNITED STATES PATENT OFFICE

FREDERICK SCHWEIGERT, OF NEW YORK, N. Y.

GUARD MEMBER FOR MOP HANDLES

Application filed April 10, 1929. Serial No. 353,923.

This invention relates to new and useful improvements in a guard member for mop heads.

The invention has for an object the provision of a device of the class mentioned which is of simple durable construction, dependable in use and efficient in action, and which can be manufactured and sold at a reasonable cost.

10 The invention proposes the use of a stationary jaw with a base strip having a concaved bottom and bearing portions arranged to hold resilient ends each consisting of wire having an outer transverse central portion 15 covered by a rubber tube and right angle arms directed inwards into the said bearing portions, and a movable jaw consisting of wire having a central transverse portion engageable in the concaved bottom of the base strip 20 and right angle arms directed upwards between the central portions of the resilient ends and the ends of the base strip. The resilient ends may be modified with the addition of springs to increase their resilient action.

25 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

30 Fig. 1 is a front elevational view of a mop head with guard members constructed according to this invention.

Fig. 2 is a vertical sectional view taken on the line 2—2 of Fig. 1.

35 Fig. 3 is a side elevational view of Fig. 1 but showing the clamping member in an open position.

40 Fig. 4 is a fragmentary bottom elevational view looking in the direction of the arrows 4—4 of Fig. 1.

Fig. 5 is a side elevational view of the stationary jaw, per se seen as though looking in the direction of the arrows 5—5 of Fig. 1.

45 Fig. 6 is a horizontal sectional view as

though taken on the line 6—6 of Fig. 1 but disclosing a modification thereof.

Fig. 7 is a similar view to Fig. 4 showing a modified form of resilient end.

Fig. 8 is a similar view to Fig. 7 showing another modified form.

The reference numeral 10 indicates generally a mop handle which has supported on its lower end a mop clamping member indicated generally by reference numeral 11 which is 60 provided with resilient ends indicated generally by numeral 12. The clamping member consists of a stationary jaw 13, a movable jaw 14 and clamping means 15.

The stationary jaw 13 has a bridge plate 16 65 with a top forward pressed semi-ring 17 and an adjacent rearward pressed semi-ring 18 both together forming a complete ring encircling the handle 10, a bottom strip portion 19 and a bottom forward pressed semi-ring 20 and an adjacent rearward pressed semi-ring 21 both together forming a complete ring encircling the handle 10. A bolt 22 is passed thru the semi-ring 17 and the handle 10 for fastening these parts together. The stationary jaw also has a base strip 24 formed with a coincaved bottom portion 25 and with bearing portions 26 on opposite edges, said bearing portions being longitudinal of the strip and parallel thereto, the strip 24 being integral with the bottom of the strip 19.

70 The movable jaw 14 is formed from a wire having a central transverse portion 27 and right angle arms 28 directed upwards. The clamping means 15 consists of a spring 29 coaxially mounted on the handle 10 and acting between the top portion of the stationary jaw and lower portion of a lever 30, which lever is formed with a front bearing loop 31 encircling one of the turns of the spring. The lever 30 is provided with side ears 32 engaged by the free ends of the arms 28. As shown in Fig. 2 these ears extend partially around the handle 10 so that the spring 29 attempts to pivot the lever 30 against the handle and thus holding the clamping means in a closed position.

75 The top end of the lever may be moved outwards for pivoting the lever about the loop 31 and initially pressing the spring until the 80

ears 32 pass a neutral line relative to the pivotal point of the lever, then the spring serves to urge the lever downwards and the clamping member may be moved to its open position 5 as illustrated in Fig. 3. In this condition of the device a mop rag may be inserted between the stationary jaw 13 and the movable jaw 14. Each of the resilient ends 12 consists of a piece of wire having an outer transverse center portion 33 and right angle arms 34 directed inwards and engaging into the ends of the bearing portions 26. The central portion 33 of the wire is covered by rubber tubing 35. When the mop is being used and is accidentally hit against the wall of a room or against furniture during use the resilient ends 15 do the striking and produce the least amount of damage since the rubber tubes absorb most of the shock. Friction is depended upon to 20 maintain the engagement of the resilient ends in the bearing portions 26.

In the modified form of the device illustrated in Fig. 6, a resilient end 12' has been disclosed formed from a wire having an inner transverse central portion 36 connected with right angle arms 37 directed outwards and at their free ends turned together as indicated by numeral 38. A rubber tube 39 is engaged upon the outer portions of the arms 30 37 and serve to absorb shocks when struck against objects. The inner transverse central portion 36 passes thru an elongated opening 40 formed in the bridge plate 19 and a tension spring 41 acts between the central portion 36 and the bridge plate for normally urging the resilient member inwards while a second spring 42 acts between the central portion and the bridge plate for urging the resilient member outwards. These springs are 35 of such tension that normally the central portion 36 assumes a position midway between the ends of the opening 40. This arrangement prevents accidental displacement of the resilient ends and in addition adds to their 40 resilient qualities.

In the modified form of the device illustrated in Fig. 7, transverse center portion 33' is shown to form an unsymmetrical shape and is covered by rubber tubing 35'. In Fig. 8 50 transverse center portion 33^a is shown to be provided with a loop 33^b so as to make a right angle arm 34'. Resilient and central portion 33^a is partially covered by rubber tubing 35^a.

55 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

60 1. The combination with a mop head hav-

ing a bottom strip portion, of a strip connected with said bottom strip and formed with bearing portions on opposite edges, said bearing portions being longitudinal of said strip and parallel thereto, a wire member having a transverse portion slightly spaced from the end of said strip and right angled co-extending arms at the ends of the transverse portion and extending into said bearing portions, and a rubber tube on said transverse portion. 70

2. The combination with a mop head having a bottom strip portion, of a strip connected with said bottom strip and formed with bearing portions on opposite edges, said bearing portions being longitudinal of said strip and parallel thereto, a wire member having a transverse portion slightly spaced from the end of said strip, right angled co-extending arms at the ends of the transverse portion and extending into said bearing portions, a rubber tube on said transverse portion, a portion connecting the inner ends of said arms and extending thru a slot in said bottom strip portion, and resilient means for balancing said wire member with the portion on the inner ends of the arms substantially at the center of said slot. 80

In testimony whereof I have affixed my signature.

FREDERICK SCHWEIGERT.
